PHASE MODULATION

John Evans, Palmyra, N. J., assignor to Radio Corporation of America, a corporation of Delaware

Application October 15, 1941, Serial No. 415,021

6 Claims. (Cl. 179—171.5)

My invention relates to radio transmitters and particularly to transmitters for producing a phase modulated or frequency modulated carrier wave.

An object of the invention is to provide an improved method of and means for producing a phase modulated or frequency modulated carrier wave.

A further object of the invention is to provide an improved circuit of the push-pull type for phase or frequency modulating the output of a stable oscillator such as a crystal oscillator.

In practicing a preferred embodiment of the invention, a crystal oscillator operating at the carrier wave frequency has its output circuit connected to a pair of radio frequency amplifier tubes in push-pull relation. The oscillator output is fed to one of the amplifiers through a capacitive circuit and to the other amplifier through an inductive circuit. These circuits include amplifier tubes to which the modulating signal is applied for varying their plate impedances. Since the input circuits of the radio frequency amplifier tubes are across these plate impedances, the phase of the radio frequency voltages at said input circuits will vary with the modulating signal, the phase shift being leading at one R. F. amplifier and lagging at the other R. F. amplifier.

The invention will be better understood from the following description taken in connection with the accompanying drawing in which

Figure 1 is a circuit diagram of one embodiment of the invention,

Figure 2 is a diagram showing a portion of Fig. 1 in simplified form, and

Figure 3 is a vector diagram which is referred to in explaining the invention.

Corresponding parts in the several figures are indicated by like reference numerals.

Referring to Fig. 1, there is shown a radio transmitter comprising a crystal controlled oscillator 10, a pair of radio frequency amplifier tubes 11 and 12 and a pair of vacuum tubes 13 and 14 to which the modulating signal is applied.

The oscillator 10 comprises a vacuum tube 16, a piezoelectric crystal 17 in the grid circuit of tube 16, and a tuned plate circuit which includes a transformer primary 18 shunted by a tuning condenser 19. This oscillator, which is of conventional design, may be replaced by any other suitable stable oscillator.

The primary coil 18 is coupled to a secondary coil 21 shunted by a tuning condenser 22. The midpoint of coil 21 is connected to ground, its upper end is connected through a variable con-

denser C1 to the control grid of tube 11, and its lower end is connected through a blocking condenser 23 and a variable inductance coil L1 to the control grid of tube 12. The impedance units C1 and L1 are adjusted to make their reactances of the same magnitude.

Amplifier tubes 11 and 12 preferably are so biased that they take very little or no grid current when carrier wave signal is applied to their control grids. With this adjustment, tubes 11 and 12 operate as class B linear amplifiers. The bias for the tubes 11 and 12 may be provided by cathode resistors 24 and 26, respectively, and supplied to the control grids of tubes through choke coils 27 and 28, respectively. The cathode resistors 24 and 26 are shunted by the usual bypass condensers indicated at 29 and 31.

The plate impedance of the amplifier tube 13 is connected across the input circuit of the R. F. amplifier 11, this connection being from the control grid of tube 11, through a blocking condenser 32 to the plate of tube 13, and through the plate-cathode impedance to ground. A suitable D. C. plate voltage is applied to the plate of tube 13 through a choke coil 33.

Similarly, the plate impedance of amplifier tube 14 is connected across the input circuit of the R. F. amplifier 12, this connection being from the control grid of tube 12, through a blocking condenser 34 to the plate of tube 14, and through the plate-cathode impedance to ground. A suitable plate voltage is applied to the plate of tube 14 through a choke coil 36.

The modulating signal is applied to the grids of tubes 13 and 14 through a transformer 37, the secondary of which has its midpoint connected to ground through a biasing source such as a battery 35. Thus, the modulating signal increases the plate impedance of one tube at the same time that it decreases the plate impedance of the other tube. It will be apparent that current at the oscillator frequency will flow through the condenser C1 and the plate impedance of tube 13 in series therewith to produce a leading voltage across said plate impedance. This leading voltage is across the input circuit of the R. F. amplifier 11.

Likewise, R. F. current will flow through the coil L1 and the plate impedance of tube 14 in series to produce a lagging voltage across said plate impedance. This lagging voltage is across the input circuit of the R. F. amplifier 12. The tubes 13 and 14 preferably are so biased that substantially no plate current flows in these tubes when there is no modulating signal being applied

through the transformer 37. Therefore, the R. F. amplifier tubes 11 and 12 continue to function as normal class B amplifier tubes when no modulating signal is being applied.

The output circuits of the R. F. amplifiers 11 and 12 include tuned plate circuits 41 and 42, respectively, coupled to secondary coils 43 and 44. The modulated carrier wave is fed from secondaries 43 and 44 to output conductors 46 through impedance matching transformers 47 and 48 which have their secondaries connected to the conductors 46 in parallel. The output circuits of amplifiers 11 and 12 may be connected in series or in push-pull to combine the amplifier outputs, if preferred. The conductors 46 may lead to R. F. amplifiers or frequency multipliers.

The D. C. plate voltage for tubes 11 and 12 may be applied through choke coils 49 and 51, respectively, which are bypassed by suitable bypass condensers 52 and 53.

Since the amplifier tubes 11 and 12 are triodes in the particular embodiment illustrated, suitable neutralization is provided for them by means of neutralizing condensers 54 and 56, respectively, these condensers being connected between the control grids of said tubes and points on the tuned plate circuits where the R. F. voltage is 180 degrees out of phase with respect to the R. F. voltage on the plates.

The operation of the phase modulating circuit is now described with reference to Figs. 2 and 3. Fig. 3 shows vectors for two different impedances of the tube 13 and for two different impedances of the tube 14, the four groups of vectors being indicated by (1), (2), (3), and (4). Assume the applied modulating signal is positive at the grid of tube 13 so that the plate impedance of this tube is decreased. There is no change at the tube 14 since it originally was biased to plate current cut-off and the grid has now simply been made more negative. Through the plate-cathode impedance of the tube 13, however, there is an increase in the flow of R. F. current i . Since the R. F. voltage E appearing across the tuned circuit 21-22 is of constant amplitude, the result is as follows:

The increased current flow causes an increase in the voltage drop E_C across the condenser C_1 . At the same time, there is a decrease in the voltage drop E_R across the plate-cathode impedance of the tube 13 due to the decrease in said impedance, the latter decrease being more than the current increase. Thus, the R. F. voltage E_R at the grid of R. F. amplifier 11 leads the voltage E appearing across tuned circuit 21-22 by an amount that increases as the plate impedance of the tube 13 is decreased. This portion of the circuit will produce a leading phase shift of nearly 90 degrees.

Assume now that the modulating signal is positive at the grid of tube 14. Now the tube 13 is at plate current cut-off and the phase shift is produced by current flow i through coil L_1 across which appears voltage E_L and through the tube 14. In this portion of the circuit, the voltage drop E_R across the plate-cathode impedance of tube 14 (which is the voltage at the grid of tube 12) lags the voltage E across tuned circuit 21-22 by an amount depending upon the said plate-cathode impedance. The more this impedance is decreased, the more the voltage at the grid of R. F. amplifier 12 lags the voltage across circuit 21-22. This portion of the circuit will produce a lagging phase shift of nearly 90 degrees.

From the foregoing, it will be apparent that I 75

have provided an improved way of shifting the phase of a stable oscillator output nearly 180 degrees, that is plus or minus 90 degrees.

In actual practice, the amount of phase shift 5 probably should be limited to about plus or minus 45 degrees because of the burden otherwise put on the limiter tubes employed for removing the 10 amplitude modulation caused by the change in length of vector E_R (Fig. 3) as the phase is shifted, and, also, because of audio signal distortion 15 that might otherwise become too great. It may be noted that, if a maximum phase shift of about plus or minus 25 degrees is produced (a total phase shift of 50 degrees), the distortion will be negligible, that is, less than two percent, for example.

It will be understood that a suitable correcting 20 network for the modulating signal may precede the transformer 37 to amplify the signal inversely with the frequency to produce a frequency modulated output as is well known in the art.

I claim as my invention:

1. In combination, a stable oscillator for producing a carrier wave, a pair of amplifiers, means 25 for coupling said oscillator to the input circuits of said amplifiers in push-pull relation, means for feeding the outputs of said amplifiers to a signal transfer circuit for combining the outputs, said means for coupling said oscillator to said input circuits including a phase advancing network through which signal is applied from said oscillator to the input circuit of one of said amplifiers, and a phase retarding network through which signal is applied from said oscillator to the input circuit of the other of said amplifiers, and means for varying alternately the phase shift produced by said networks in accordance with a modulating signal.

2. In combination, a stable oscillator for producing a carrier wave, a pair of amplifiers, means 40 for coupling said oscillator to the input circuits of said amplifiers in push-pull relation, means for feeding the outputs of said amplifiers to a signal transfer circuit for combining the outputs, said coupling between said oscillator and said input circuits including a phase advancing network through which signal is applied from said oscillator to the input circuit of one of said amplifiers, and a phase retarding network through which signal is applied from said oscillator to the input circuit of the other of said amplifiers, each of 45 said networks including an electron discharge device having a cathode and control grid, and means including a push-pull connection to said devices for differentially controlling the impedances thereof in accordance with a modulating signal, and means for biasing the control grids of said devices negative relative to the respective cathodes of said devices by an amount such that substantially no plate current flows in 50 said devices in the absence of modulating signals.

3. In a signalling system, a source of oscillations of carrier wave frequency, a pair of amplifier tubes each having input electrodes, means 55 for coupling said oscillator to the input electrodes of said amplifiers in push-pull relation, means for feeding the outputs of said amplifiers to a signal transfer circuit for combining the outputs, a pair of modulating vacuum tubes biased 60 to plate current cut-off and having input electrodes coupled in push-pull relation to a source of modulating signal, a phase advancing network in said first coupling through which signal is applied from said oscillator to the input electrodes of one of said amplifiers, and a phase re- 65

tarding network in said first coupling through which signal is applied from said oscillator to the input electrodes of the other of said amplifiers, one of said networks including one of said modulating tubes and the other of said networks including the other of said modulating tubes.

4. In a modulation system, a stable oscillator for producing a carrier wave, a pair of amplifiers each having input and output electrodes, a carrier frequency excitation circuit coupling said oscillator to the input electrodes of said amplifiers in push-pull relation, a signal transfer circuit coupled to the output electrodes of said amplifiers whereby the outputs of said amplifiers are fed to said signal transfer circuit for combining the outputs, a pair of modulating vacuum tubes having input circuits connected in push-pull relation to a source of modulating signal, said modulating tubes being biased to plate current cut-off when no modulating signal is being applied, connections coupling the plate-cathode impedance of one of said modulating tubes across the input circuit of one of said amplifiers, connections coupling the plate-cathode impedance of the other of said modulating tubes across the input circuit of the other of said amplifiers, a capacitive reactance unit connecting a portion at least of said excitation circuit in series with one of said plate-cathode impedances, and an inductive reactance unit connecting a portion at least of said excitation circuit in series with the other of said plate-cathode impedances.

5. In a wave length modulation system, a source of wave energy the wave length of which is to be modulated, a source of modulating signals, a pair of electron discharge devices each having input electrodes and having output electrodes coupled to an output circuit, a pair of modulator tubes each having electrodes between which there is impedance and an impedance con-

- 40 trol electrode, a phase advancing network and a phase retarding network coupling the input electrodes of said devices in push-pull relation to said source of wave energy, said networks each 5 including the impedance of a different one of said tubes, a differential coupling between said source of modulating signals and said tubes, and means for impressing on the impedance control electrode of each tube a bias such that substantially no plate current flows in the said tubes in the absence of modulating signals.
- 10 6. In a signalling system, a stable oscillator for producing a carrier wave, a pair of amplifiers each having an input and an output, connections 15 coupling said oscillator to the inputs of said amplifiers in push-pull relation, a signal transfer circuit coupled to the outputs of said amplifiers, a pair of modulating vacuum tubes having inputs connected in push-pull relation to a source of 20 modulating signal, said amplifier tubes each having a plate and cathode, connections coupling the plate-cathode impedance of one of said modulating tubes across the input of one of said amplifiers, said last named connections also coupling said plate-cathode impedance of said one tube in series with one of said first named connections, connections coupling the plate-cathode impedance of the other of said modulating tubes across the input of the other of said amplifiers, said last 25 named connections also coupling said plate-cathode impedance of said other tube in series with another of said first named connections, a capacitive reactance unit in the series connection of said one of said plate-cathode impedances and said one of said first connections, and an inductive reactance unit in the series connection of said other of said plate-cathode impedances and said other of said first named connections.
